UNITED STATES PATENT OFFICE.

JAMES LYONS, OF NEW YORK, N. Y.

CHECK-BOOK.

1,283,241.

Specification of Letters Patent. Patented Oct. 29, 1918.

Application filed December 29, 1916. Serial No. 139,501.

To all whom it may concern:

Be it known that I, JAMES LYONS, a citizen of the United States, residing at New York, in the county of New York and State of New York, have invented certain new and useful Improvements in Check-Books; and I do hereby declare the following to be a full, clear, and exact description of the invention, such as will enable others skilled in the art to which it appertains to make and use the same.

This invention relates to improvements in bank check books having means for retaining canceled checks, and the object is to file the canceled checks so that they may be exposed along with their respective stubs for easily finding the canceled checks by reference to their stubs.

With this and other objects in view as will 20 in part hereinafter become apparent and in part be stated, the invention comprises certain novel constructions, combinations and arrangements of parts as subsequently specified and claimed.

25 In the accompanying drawing,—

Figure 1 is a view in plan of a book embodying the features of the present invention, the book being illustrated in an open condition and a fragment of that portion of 30 the cover of the book which covers the stubs being broken away.

Fig. 2 is an edge view of the parts seen in Fig. 1.

Fig. 3 is a perspective view of the book in 35 its closed condition.

Fig. 4 is a fragmentary, sectional view of a modified embodiment.

It will become obvious that the invention 40 appertains as well to notes, and other like papers as to checks, but for facility and convenience of expression the term "check" will be used throughout this specification and claims to signify any such papers, and the appended claims are to be accordingly interpreted.

Referring to the drawing by numerals, 1 indicates the usual binding for a check book, such as is common on the market, the said binding retaining the usual stubs 2 and engaging the bottom cover 3 and the stub-covering section 4 of the top cover. The check covering portion 5 of the top cover is severed from the stub-covering portion 4 and has its outer end connected with the 55 bottom cover 3 by a binding strip 6 of any appropriate material. At the end of the

cover portion 5 engaged by the binding strip 6, the said cover portion is formed with apertures 7, 7, adapted to receive check-retaining devices, such as the paper fasteners 8, 8 for securing the cover portion 5 to the bottom cover 3 and for holding the check retaining devices 8 in place. Detachably connected to the stubs 2 in the usual manner are the checks 9, all of which are apertured 60 at 10, 10 at their outer ends for enabling the several checks to be applied onto the fasteners 8 after the checks have been canceled and returned.

The operation should be obvious, and consists in disposing the parts as indicated in Fig. 3 when the check book is not in use. When it is desired to use a check, the top cover portion 5 is lifted and swung outward on the strip 6 as a hinge until the parts 70 assume the position indicated in Figs. 1 and 2. The check is made out, torn from its stub and used in the usual manner. After the check has been paid and returned by the bank, the check book being disposed as indicated in Figs. 1 and 2, the paid check is applied onto the fasteners 8 face downward, thus bringing the check directly opposite its 75 respective stub when the parts are folded as indicated in Fig. 3.

The cover portion 5 is creased or otherwise formed with a hinge 11 extending across the said cover portion near the binding strip 6, so that when the parts are in the position indicated in Fig. 3 the cover portion 5 may be elevated but the canceled checks will be left in position opposite their respective stubs. The user can then search 80 through the stubs, by lifting up the cover portion 4, until he comes to the particular stub sought after, and he can then similarly search through the canceled checks until he finds the check corresponding to the stub. He then has before him the full data of the 85 entire transaction.

In Fig. 4 is illustrated a slightly modified embodiment in which the apertures 10' are extended through the top and bottom covers as well as through the checks 9', and a loose leaf binder ring 6' is employed whereby the 90 need for the hinge 11 is obviated. The operation with respect to this structure is the same as that described except that the ring 6' must be withdrawn either for removing a new check or for inserting a canceled one. 105

The cover portion 5 is provided with the hinge 11 near the binding strip 6 so that

the major portion of the part 5 may be swung up into open position when the book is closed, as shown in Fig. 3, for admitting inspection of the canceled checks which are held by the attaching means 8 in proper position with their faces uppermost.

What I claim is:—

- 5 1. A bank check book comprising a pad of printed stubs adapted to be filled in in the usual manner, checks detachable from the stubs, top and bottom covers, and means binding all of said parts together; the top cover being severed along a line registering with the line between the stubs and the checks, a hinge connection between the check-covering portion of the top cover and the end of the bottom cover remote from the stubs, and fastening means carried by said check-covering portion of the top cover near its hinged end for receiving and retaining the checks, and adapted to receive thereon the ends of the checks remote from their stub ends when the checks are removed from the stubs and canceled.
- 10 2. A check book comprising a pad of stubs and checks detachable therefrom, top

and bottom covers, and means binding all of said parts together; the top cover being severed along a line registering with the line between the stubs and the checks, a hinge connection between the check-covering portion of the top cover and the end of the bottom cover remote from the stubs, and fastening means carried by said check-covering portion of the top cover near its hinged end for receiving and retaining the checks, and adapted to receive thereon the ends of the checks remote from their stub ends when the checks are removed from the stubs and canceled.

In testimony whereof I affix my signature in presence of two witnesses.

JAMES LYONS.
